PEBBLE HEATER APPARATUS AND METHOD
FOR HEAT EXCHANGE

Cruzan Alexander and Harris A. Dutcher, Bartlesville, Okla., assignors to Phillips Petroleum Company, a corporation of Delaware

Application May 2, 1946, Serial No. 666,767

19 Claims. (Cl. 196—55)

1

This invention relates to the treatment of fluids. In one particular aspect this invention relates to pebble heaters for the heating of gases to high temperatures. In still another aspect this invention relates to a method and apparatus for heating hydrocarbons to relatively high temperatures for conversion thereof to other hydrocarbons and hydrogen-containing gases. Another aspect of this invention relates to a reaction chamber and a method for heating the same.

In hydrocarbon conversion processes which require high temperature and which are endothermic in character, such as thermal cracking and thermal dehydrogenation of hydrocarbons, pebble heater type apparatus functions most satisfactorily. Also in the superheating of gases, such as steam, pebble heaters may also be applicable. The pebble heater methods entail the heating of refractory pebbles in a heating chamber by the combustion of fuels and the transference of resulting hot pebbles to a second heating or conversion chamber for heating the fluids being processed and furnishing the heat of reaction. In the conventional pebble heater type furnace a continuous stream of hot pebbles is passed through the conversion chamber by gravity flow and transferred by means of a bucket type elevator or other mechanical lifting device to the pebble heater for reheating and recycling through the system.

In processes which function most advantageously at extremely high temperatures—for example, in vapor phase thermal cracking of light hydrocarbons to produce lighter products, the pebbles leaving the cracking chamber are still at a very high temperature and can be handled in mechanical conveyor equipment only if high temperature alloy materials are used. Furthermore, in conventional apparatus it is difficult if not impossible to obtain the high temperatures that are so advantageous in cracking of the lighter hydrocarbons wherein temperatures of 1500 to 2000° F. or higher are often necessary. Consequently, it is highly desirable to provide a pebble heating type apparatus and reaction chamber which requires few mechanical moving parts.

An object of the present invention is to provide a method and apparatus for the attainment of extremely high temperatures in a pebble heater type furnace.

Another object is to provide a novel apparatus for supplying heat to or removing heat from gases.

Still another object of the present invention is to provide an apparatus for heating and reacting materials in a single unitary apparatus.

2

Another object is to provide an apparatus having the characteristics of the conventional pebble heater type furnace without the necessity of mechanical conveyors for conveying the pebbles.

5 It is a further object to provide a method and apparatus for heating gases with pebbles whereby large temperature changes of the pebbles are minimized.

Various other objects and advantages will be 10 come apparent to those skilled in the art from the accompanying description and disclosure.

For a full understanding of the nature and objects of invention, reference should be had to the following detailed description taken in connection 15 with the accompanying drawing.

In the drawing—

Figure 1 is an elevational view, partially in cross section, diagrammatically illustrating apparatus for heating a fluid according to the present 20 invention.

Figure 2 is another modification of the present invention also shown in an elevational view, partially in cross section, illustrating apparatus for heating a fluid.

25 In Figure 1, which diagrammatically illustrates one arrangement of apparatus for this invention, numeral 8 designates an elongated, enclosed, hollow body which contains both a combustion zone and a heating or reaction zone. The hollow body is divided into a reaction zone 23, an intermediate zone 25 and a combustion zone 7 by septa 18 and 11, respectively. The form of the hollow body is preferably cylindrical as a matter of convenience in both construction and operation, but hollow body 8 may be of any other particular form as desired. Hollow body 8 can be constructed of various types of metals, such as steel, nickel and chrome alloy steels, or Inconel, and, preferably, is lined or covered both on the inside and the outside thereof by suitable materials (not shown). The lining on the inside of cylinder 8 will usually comprise refractory material, such as those materials which are resistant to high temperatures and to spalling by the pebbles. Suitable materials for such purposes, for example, are kaolin, alumina-diaspore, sillimanite, bonded silicon carbide, bonded fused alumina, etc. The covering on the outside of cylinder 8 is usually asbestos, or the like, for preventing the loss of heat from cylinder 8. Under some circumstances cylinder 8 is constructed entirely of ceramic refractory material and may be constructed in sections, each section of the same or different material, without departing from the scope of this invention.

50 According to the preferred form of apparatus 55

3

of this invention, septum 18 is perforated and contains a vent or lumen, preferably in the center thereof, as shown by numeral 19. Septum 18 may be constructed of any type of material which is resistant to high temperatures and which has sufficient strength to support its own weight and the weight of a layer of pebbles on the top thereof. In some instances septum 18 is made of a metal, such as a high alloy metal as Inconel; in other instances it is constructed of suitable ceramic or porcelain material. Usually the construction of septum 18 is of a metal and is in the form of a perforated disc or plate, or a wire screen, so that pebbles collect on the top thereof in a layer and flow through the holes or perforations therein into chamber 25 below. Septum 11 may be constructed of materials similar to those described with respect to the construction of septum 18. The form of septum 11, however, is somewhat different, preferably, in the form of a funnel-shaped member having a vent or opening, generally in the center thereof, for passage of fluid therethrough. Septum 11 may also be of a relatively greater thickness (as shown) than septum 18 and capable of supporting a relatively deep layer of pebbles on the top thereof. When septum 18 is of such a relatively massive construction, it will be made of ceramic material. When septum 11 is constructed more or less as a thin plate or sheet in the form of a funnel or cone, it will be made of metal.

Element 13 is an elongated conduit open at both ends and is positioned concentrically to vent 16 of septum 11. The lower end of conduit 13 terminates adjacent and above vent 16. The length of conduit, preferably, constitutes only a minor proportion of the length of the intermediate chamber 25 and serves as a passageway for the flow of gases and pebbles from chamber 25 to reaction chamber 23. In other words, the length of conduit 13 is usually less than about one-half the length of chamber 25. Conduit 13 is supported at the proper location in chamber 25 by suitable rods or beams 14. Conduit 13 is constructed of a suitable material, such as porcelain, Inconel, or the like. Element 12 provides a restricted area in the lower end of conduit 13 and operates as a nozzle. Fuel and air are introduced through conduits 4 and 5 into combustion chamber 7 in which combustion of the fuel and air is effected. The combustion products or flue gases pass from combustion chamber 7 through vent 16, conduit 13 into intermediate chamber 25. Flue gases are removed from intermediate chamber 25 through conduits 24. The fluid to be treated or heated is passed into the lower portion of zone 23 through conduits 26 and the resulting effluent is removed from the top of zone 23 through conduit 28 and valve 29. Element 27 is a shield or like means for deflecting pebbles and preventing their passage from chamber 23 through conduit 28.

Valve 29 is a conventional motor or automatic control valve which is actuated by transmission means 31 electrically or pneumatically responsive to the pressure in intermediate chamber 25. For the various types of hook-ups of an automatic valve and its operation reference is made to the adequate description in "Industrial Instruments for Measurement and Control," Rhodes, T. J., McGraw-Hill Book Company, 1941.

Septum or screen 18 is perforated with the appropriate number and size of holes to maintain a desired depth of pebbles, shown at 21, on the septum and at the same time to permit pebbles

4

to fall through the perforations. Conduit 13 is located close to septum 11 so that pebbles accumulate on the top of septum 11, as indicated by numeral 22, and simultaneously continuously flow through the annular space between septum 11 and the lower end of conduit 13 into the gas stream from vent 16.

Various modifications, alterations of the elements of Figure 1 may be practiced without departing from the scope of this invention. As shown, feed entering through conduits 26 is introduced in tangential direction; however, the feed may be introduced without a tangential direction if desired. Furthermore, flue gases being removed through conduits 24 may be removed in a tangential direction if desired. Vent or lumen 19 may be constructed in any form and may extend further into reaction zone 23 than shown. In some instances it may be desired and preferable to eliminate combustion zone 7 and in so doing the combustion gases and air are introduced directly through vent 16 and are burned in conduit 13. Combustion zone 7 may be a separate unit from cylinder 8 and the effluent from zone 7 is passed to inlet or vent 16 through suitable conduits (not shown). A screen or the like (not shown) may be placed over the top of vent 16 in order to prevent pebbles falling from zone or chamber 25 to combustion zone 7. Nozzle or restriction 12 may also be omitted if desired and conduit 13 may comprise a bundle or group of small conduits (not shown) which together comprise conduit 13.

A heat exchanger (not shown) may be provided for heat exchange of the flue gases in conduits 24 with incoming feed in conduits 26 or with air in conduits 5.

In Figure 2, which diagrammatically shows another modification of apparatus for practicing the present invention, element 53 as in Figure 1 is an elongated, enclosed, hollow body, preferably of a cylindrical shape. Cylinder 53 is separated into an upper chamber 72, a reaction chamber 71 and a combustion chamber 57 by a perforated septum 68 and a funnel-shaped septum 59, respectively. The construction and materials are similar to those of the apparatus described in Figure 1, and, therefore, such description is unnecessary with regard to Figure 2. As in Figure 1 septum 68 may comprise a wire screen or the like for the collection of pebbles thereon.

A conduit 62 is passed through screen or septum 68 in open communication between chamber 72 and the lower portion of reaction chamber 71 as shown. Conduit 62 is held in position in reaction zone 71 by means of supporting rods 66. Conduit 62 is preferably an elongated cylindrical pipe or tube and is positioned so that it protrudes through the center of septum 68 and extends substantially the entire length of chamber 71 and terminates adjacent a vent 58 of septum 59. Vent 58 is preferably located in the center of septum 59. Fuel and air are introduced into combustion zone 57 through conduits 54 and 56, respectively. The products of combustion are passed from combustion zone 57 to zone 72 through conduit 62 and are removed therefrom through a conduit 74. Conduit 76 is a fluid inlet for introduction of feed into the upper portion of reaction zone 71. Withdrawal of an effluent from zone 71 is effected through conduit 78. The lower portion of conduit 62 may be restricted in cross sectional area by element 61. Element 13 comprises a guard or shield for preventing the passage of pebbles from chamber 72 through conduit 74 which removes

the heating fluid from chamber 72. Numerals 63 and 69 indicate the accumulation of pebbles in the lower portion of reaction chamber 71 and chamber 72, respectively.

As described in Figure 1, various alterations and modifications may be effected in the apparatus shown in Figure 2 without departing from the scope of this invention. Preferably, conduit 78 is located in the lower portion of reaction zone 71 below the accumulation of pebbles 63 therein but alternatively it may be located above the accumulation of pebbles 63. Fluid introduced into chamber 71 through conduit 76 passes through the accumulation of pebbles 63 and out of reaction zone 71 through conduit 78. Conduit 62 extends substantially the entire length of zone 71 and is sealed therefrom by the accumulation of pebbles 63 at the lower portion of zone 71. Any desired height of pebbles may be maintained in zone 71.

The term "pebble" as used throughout the specification denotes any refractory material, either ceramic or metallic, in flowable form and size which can be utilized to carry heat from one zone to another. Pebbles are conventionally substantially spherical and are from as large as about 1 inch in diameter to as small as will pass through a 200 mesh screen. The actual size of the pebbles will of course depend upon character of the refractory material, such as its density, and upon the gas velocity of the supporting fluid stream. In general, the pebbles must be of refractory material which will withstand temperatures as high as the highest temperature attained in the pebble heating zone. Pebbles which will withstand temperatures within the range of about 3000 to 3500° F. are now in use and comprise highly heat resistant material, such as fused alumina. The preferred size of the pebbles when using a ceramic refractory material is about that size which will pass through an 8 mesh screen and will be retained on a 60 mesh screen. The pebbles themselves may comprise a catalytic material or may comprise an inert material impregnated with a catalytic material for the process in which they are being used. Therefore, in many instances the pebbles will comprise a metallic catalyst or will comprise a ceramic material impregnated with a metallic catalyst.

Operation

In the operation of Figure 1, a feed which may comprise hydrocarbon reactants or an inert gas to be superheated is continuously or intermittently passed into reaction zone 23 through conduit 26. The feed material in reaction zone 23 undergoes the desired treatment and achieves the desired temperature by contact with pebbles therein. After the gas has remained in chamber 23 for sufficient length of time to achieve the appropriate temperature it is continuously or intermittently removed therefrom through conduit 28 and valve 29.

In order to heat the pebbles to a sufficiently high temperature to transfer heat to the gas in chamber 23, fuel and air enter combustion zone 7 through conduits 4 and 5, respectively, and are burned therein. The flue gas or combustion products from combustion zone 7 continuously pass through an orifice or vent 16 into chamber 25 and pass upward through conduit 13 at a high rate of speed as the result of the expansion of the hot gases. The rate of flow of gases passing through orifice or vent 16 is substantially in excess of the flame propagation of the combustion

gases. Therefore according to one modification, air and fuel are mixed in zone 7 and pass through vent 16 through conduit 13 where the fuel is ignited. The flame in conduit 13 and chamber 25 cannot progress into chamber 7 because the speed of the gases through vent 16 is greater than the rate of flame propagation. In either of the above methods of operation, the gases from the chamber 7 passing through conduit 13 achieve a very high rate of speed in excess of about 10 to about 15 feet per second and often as high as about 30 to about 40 feet per second, which speed depends to a large extent upon the cross sectional area of the inside of conduit 13. The high rate of speed of the gases passing from vent 16 into conduit 13 through restricted area 12 aids in continuously forcing pebbles which have accumulated at 22 into the gaseous stream by an inspiriting effect. The pebbles falling into conduit 13 are heated and suspended in the gaseous stream which throws them upward from the upper end of conduit 13 through vent 19 and into upper chamber or reaction zone 23. When the pebbles comprise a catalytic material, the heating of the pebbles in conduit 13 also regenerates or reactivates the catalytic material. Because of the sudden increase in cross sectional area confining the gases when they pass from conduit 13 into the open space of chamber 25, the velocity of gaseous stream rapidly decreases. Flue gases are removed from chamber 25 through conduits 24. However, because of the inertia and momentum of the pebbles, the heated pebbles pass upward through vent 19. In chamber 23 the pebbles lose their velocity and fall downward onto screen 18. Some of the pebbles may have sufficient velocity to impinge upon shelf 27 which changes their direction and makes them drop onto screen 18. The size of the perforations in screen 18 with regard to the size of the pebbles and to the rate at which they accumulate is such that a layer of pebbles 21, often several inches in thickness, is continuously maintained on the top side of screen 18. The pebbles fall through screen 18 at substantially the same rate as they accumulate thereon. The layer of pebbles 21 on screen 18 prevents or hinders the passage of gases from reaction zone 23 to chamber 25 or vice versa; thus the intermingling of gases from each chamber is prevented or minimized. As shown the feed enters reaction zone 23 is a tangential direction to attain a tangential motion and by this motion the feed aids in spreading out the stream of pebbles flowing from chamber 25 into chamber 23 and ensures an even distribution of pebbles on screen 18.

Mechanical means for shaking screen 18 (not shown) may be used to aid in forcing the pebbles through the perforations in screen 18 and also by controlling the amount of shaking the height of the pebbles on screen 18 can be adjusted.

The pebbles give up the heat acquired in conduit 13 and chamber 25 to the incoming fluid feed in reaction chamber 23. After accumulation on screen 18 the pebbles continuously fall through the perforations therein and drop by gravity into the lower portion of chamber 25 for reheating. The funnel-shaped septum 11 in the lower portion of chamber 25 accumulates the pebbles around the lower end of conduit 13 and around vent 16. The space between the lower end of conduit 13 and the surface of funnel-shaped septum 11 serves as a proportioning device for the flow of pebbles from chamber 25 into the high speed gas stream from vent 16.

In circumstances where it is objectionable or undesirable for any gases from chamber 23 to pass into chamber 25, a higher pressure may be maintained in chamber 25 than in chamber 23 by means of valve 29 and transmission means 31 responsive to the prevailing pressure in chamber 25. If a slightly excess pressure, e. g. between about 2 and about 5 pounds per square inch difference, is maintained in chamber 23, a small amount of gases continuously flows from chamber 23 to chamber 25 through vent 19 while at the same time pebbles are passing upward from chamber 25 to chamber 23 through vent 19. The pebbles in chamber 23 which are at a very high temperature, such as about 1500 to about 3000° F., give off much of their available heat before falling into lower chamber 25 where they are re-heated.

Since the operation in Figure 2 in most respects is similar to the operation in Figure 1, only a brief discussion of the operation of apparatus illustrated in Figure 2 will be made. Figure 2 is another modification of the present invention showing apparatus for the heating (or cooling) of gases. A fluid feed enters zone 71 of cylinder 53 through conduit 76. This feed contacts falling pebbles in zone 71 and passes through the accumulation of pebbles 63 in the lower portion of zone 71 and thence from cylinder 53 through conduit 78 which may have a screen (not shown) over the mouth thereof to retain pebbles in zone 71. It should be noted that in the preferred method of operation shown, the accumulation of pebbles 63 in zone 71 is such that the gases from conduit 76 must pass through the accumulation of pebbles before being removed from cylinder 53. Fuel and air are passed into combustion zone 57 through conduits 54 and 56, respectively. The combustion mixture is burned in zone 57 and the hot combustion products or flue gases are continuously passed from zone 57 through vent or orifice 58 into elongated conduit 62 through restricted area 61. Since the fluid flowing through vent 58 and restricted area 61 into conduit 62 is at a high velocity, pebbles fall into the flowing gaseous stream by an inspiration effect as well as by their own weight and are heated and suspended in the hot gaseous stream. In this embodiment of the invention the gases flow in conduit 62 only at a sufficient rate to suspend the pebbles and convey them along with the hot flue gases through conduit 62 to upper chamber 72. In upper chamber 72, because of the increased cross sectional area of that zone, the gases lose much of their velocity. The suspended pebbles fall onto screen 68, as shown. Those pebbles which may have enough velocity to pass to the upper portion of chamber 72 impinge against shield 73 and are deflected downward onto screen 68. The accumulation of pebbles on screen 68 indicated by numeral 69 prevents the passage of gases from chamber 72 to chamber 71, as described with respect to Figure 1.

Pebbles at a relatively high temperature, e. g. 1500 to 2500° F., drop through perforations in screen 68 and fall by gravity through chamber 71 to the lower portion thereof and accumulate as indicated by 63. In chamber 71 the pebbles give up the heat acquired in conduit 62 to the feed entering through conduit 76.

As in the case of Figure 1 combustion zone 57 may comprise only a mixing zone and combustion may take place entirely in conduit 62 and upper chamber 72 without departing from the scope of this invention. Even in some instances zone 57 may be separate from cylinder 53 (or 75) which enables economical construction and op-

zone 7 from cylinder 8 of Figure 1) without departing from the scope of the invention.

A particular novelty of the modification shown in Figure 1 lies in the fact that the pebbles from the heating zone 25 pass to reaction zone 23 by their own inertia and momentum achieved by their suspension in the gaseous stream in conduit 13. On the other hand a particular novelty of the modification shown in Figure 2 lies in the fact that the pebbles accumulating in reaction zone 71 are passed therefrom by being supported in a gaseous stream in conduit 62 throughout their passage from zone 71 to upper zone 72. For the operation of Figure 1 a higher velocity of gases must be maintained in conduit 13 than is usually maintained in conduit 62 of Figure 2, because in Figure 1 the pebbles are passed to the upper zone 23 by force of their inertia and momentum while in Figure 2 the pebbles are passed into upper zone 72 by a suspension or gas lift effect. Although Figure 2 comprises the preferred modification of the present invention, in some instances it may be more desirable and more practical to use the type of apparatus and method shown in Figure 1.

The feed entering cylinder 53 through conduit 76 of Figure 2 may be introduced tangentially as in the case of Figure 1. Furthermore, the feed of Figure 2 may be introduced through conduit 78 and the resulting product removed through conduit 76 without departing from the scope of this invention.

It is possible in some instances to operate zone 23 of Figure 1 as the combustion zone for heating the pebbles and zone 25 and conduit 13 as the reaction zone. Thus, the reactant gases are introduced into zone 25 through inlet 16 and are removed therefrom through conduits 24. Air and fuel are introduced into zone 23 through lines 26 and a flue gas is removed through line 28. The reactant gases themselves suspend the pebbles in conduit 13 according to this modification.

The present invention may be applied to exothermic reactions as well as endothermic reactions. For example, feed introduced through conduits 54 and 56 in Figure 2 may undergo an exothermic reaction in chamber 57. The reaction effluent passes from zone 57 through conduit 62 at a rate such that cool pebbles are supported therein and absorb heat from the reaction effluent. The pebbles are then discharged from conduit 62 into zone 72 where they drop back into cooling zone 71, as shown, but at a substantially higher temperature than when introduced into conduit 62. The pebbles then give up their heat in cooling zone 71 and pass downward to absorb heat from the reaction effluent passing through conduit 62. The cooling medium is introduced into cooling zone 71 through conduit 75 or 78 and removed therefrom through conduit 79 or 76. This and many other modifications may be practiced without departing from the scope of this invention in either the apparatus shown in Figure 1 or in Figure 2.

Various advantages of the present invention are apparent. Pebble heaters constructed in the manner described in this application do not have the conventional pebble conveying equipment. The pebbles are transferred according to this invention from one zone to another without the usual mechanical conveyor. Other usual mechanical features of pebble heaters are also eliminated, such as star valves, conduits, throats, etc. Furthermore, the pebble heater itself is unitary which enables economical construction and op-

eration of the pebble heater. The shorter distances between the zones and the minimum amount of contact with the surfaces avoids excessive stressing and disintegration of the pebbles. Since the range between the maximum and minimum temperatures of the pebbles themselves is decreased according to this invention, disintegration of the pebbles is minimized.

The use of apparatus as shown in Figure 2 may be conveniently applied to the superheating of steam and as a typical example of such a process the following application will be described. A power unit requiring approximately 1000 pounds of steam per hour at a temperature of about 1000° F. utilizes the apparatus of Figure 2 in the following manner. Steam is passed through chamber 71 at the rate of about 1000 pounds per hour at a pressure of about 20 pounds gage and at an entrance temperature of about 280° F. The steam in a superheated condition leaves zone 71 through conduit 78 at about 1000° F. A hydrocarbon fuel, such as butane, is burned in zone 57 with excess air. The flue gas from combustion zone 57 passes through a 3 inch diameter conduit 62 at a rate of about 30 feet per second. The pebbles of quartz or sand used for such operation preferably have a diameter of about 0.006 of an inch and are readily suspended in the fluid in conduit 62 and are heated above about 1500° F. The diameter of conduit 62 is about 3 inches inside diameter and the diameter of cylinder 53 is about 2 feet. Conduit 62 is about 4 to 6 feet in length depending upon the depth of the pebbles accumulating in reaction zone 71.

The apparatus and method for heating gases as described in this application may be used for various other processes than those specifically mentioned. Other chemical reactions to which the present invention is applicable comprise dehydrogenation of hydrocarbon, the formation of water-gas from hydrocarbons and steam, the hydrogenation of carbon monoxide, depolymerization and dealkylation, etc.

It is to be understood that the form of our invention herewith shown and described is to be taken as preferred example of the same, and that various changes in shape, size and arrangement of parts may be resorted to without departing from the spirit of this invention or the scope of the subjoined claims.

Having described our invention, we claim:

1. Apparatus for the treatment of a gas which comprises in combination an enclosed, hollow body having an outlet at the top thereof and an inlet at the bottom thereof, a first perforate septum having a vent for the passage of gas therethrough positioned across said hollow body and forming an upper chamber in said body, a second imperforate septum having a vent for the passage of gas therethrough positioned across said hollow body so as to form a lower chamber below said second septum and an intermediate chamber between said first and second septa, means for introducing a gas into said upper chamber, means for removing gas from said intermediate chamber, and a conduit positioned in said intermediate chamber in vertical alignment with said vents and in close spaced-apart relation to the vent in said second septum.

2. Apparatus for the treatment of gas in the presence of pebbles which comprises in combination a vertical elongated enclosed vessel having an outlet at the top thereof and an inlet at the bottom thereof, a first perforate septum having a vent for the passage of pebbles therethrough positioned across said vessel so as to form an up-

per chamber therein, a second imperforate septum having a vent for the passage of gas therethrough positioned across said vessel so as to form a lower chamber below said second septum and an intermediate chamber between said first and second septa, means for introducing gas into said upper chamber, means for removing gas from said intermediate chamber, and conduit means aligned with said vents and extending upwardly from close proximity to the vent in said second septum adapted for lifting pebbles by means of high velocity gas to said upper chamber.

3. Apparatus for the heat exchange of gases which comprises in combination an upright enclosed cylindrical vessel having a gas outlet at the top and a fluid inlet at the bottom thereof, a first perforate septum positioned in said vessel whereby an upper chamber is formed in said body, a second imperforate septum having a central vent for the passage of gas therethrough positioned in said vessel so as to form a lower chamber below said second septum and an intermediate chamber between said first and second septa, an elongated conduit openly communicating between said upper chamber and said intermediate chamber passing through the center of said first septum and extending downward and terminating in close spaced-apart relation to the vent in said second septum so as to effect the passage of pebbles from the bottom of said intermediate chamber into and through said conduit to said upper chamber upon the passage of an upward blast of gas through said vent into said conduit, means for introducing feed gas into said intermediate chamber, and means for withdrawing effluent gas from said intermediate chamber.

4. Apparatus for the treatment of a gas which comprises in combination an enclosed upright vessel having an outlet at the top thereof and an inlet at the bottom thereof, a first perforate septum positioned in said vessel and forming an upper chamber in said vessel, a second imperforate septum having a vent for the passage of gas therethrough positioned in said vessel so as to form a lower chamber below said second septum and an intermediate chamber between said first and second septa, a conduit openly communicating between said upper chamber and said intermediate chamber passing through said first septum and extending downward and terminating directly over but spaced apart from said vent in said second septum, means for introducing gas into said intermediate chamber, and means for withdrawing gas from said intermediate chamber.

5. Apparatus for the treatment of a gas in the presence of pebbles which comprises in combination an enclosed upright vessel having an outlet at the top thereof and an inlet at the bottom thereof, a first perforate septum having a central vent positioned in said vessel so as to form an upper chamber therein, a second imperforate septum having a vent for the passage of gas therethrough positioned in said vessel so as to form a lower chamber below said second septum and an intermediate chamber between said first and second septa, means positioned in said vessel for transferring pebbles from the lower portion of said intermediate chamber to said upper chamber comprising a tube element aligned with said vents in spaced-apart relation to the vent in said second septum, means for introducing feed gas into said intermediate chamber, and means for withdrawing effluent gas from said intermediate chamber.

6. Apparatus for the heat exchange of gases in the presence of pebbles which comprises in combination an upright elongated cylindrical vessel having a gas outlet at the top and a gas inlet at the bottom thereof, a first perforate septum having a central vent for the passage of pebbles upwardly therethrough positioned across the upper portion of said vessel and forming an upper chamber therein, said septum being adapted for uniformly passing pebbles downwardly over the area thereof while maintaining a multiple layer of pebbles thereon, a second imperforate funnel-shaped septum having a central vent for the passage of a hot gas therethrough positioned across the lower portion of said vessel so as to form a lower chamber below said second septum for the combustion of fuel therein and an intermediate chamber between said first and second septa, means for introducing gas tangentially into the lower portion of said upper chamber, means for removing gas from the upper portion of said intermediate chamber, an elongated open conduit positioned in said intermediate chamber in alignment with said vents and extending from adjacent the vent in said second septum only a portion of the length of said intermediate chamber, said conduit having a restricted opening in the lower end thereof and being positioned so as to effect the passage of pebbles from the bottom of said intermediate chamber into and through said conduit and said intermediate chamber to said upper chamber upon passage of an upward blast of gas through said vent in said second septum into said conduit.

7. The apparatus of claim 6 in which said conduit extends only a minor portion of the length of said intermediate chamber.

8. Apparatus for the heat exchange of gases in the presence of pebbles which comprises in combination an upright elongated cylindrical vessel having a gas outlet at the top and a gas inlet at the bottom thereof, a first perforate septum having a central vent for the passage of pebbles upwardly therethrough positioned across the upper portion of said vessel and forming an upper chamber therein, said septum being adapted for uniformly passing pebbles downwardly over the area thereof while maintaining a multiple layer of pebbles thereon, a second imperforate funnel-shaped septum having a central vent for the passage of a hot gas therethrough positioned across the lower portion of said vessel so as to form a lower chamber below said second septum for the combustion of fuel therein and an intermediate chamber between said first and second septa, means for introducing gas tangentially into the lower portion of said upper chamber, means for removing gas from the upper portion of said intermediate chamber, and an elongated open conduit positioned in said intermediate chamber in alignment with said vents and extending from adjacent the vent in said second septum only a portion of the length of said intermediate chamber, said conduit having a restricted opening in the lower end thereof and being positioned so as to effect the passage of pebbles from the bottom of said intermediate chamber into and through said conduit and said intermediate chamber to said upper chamber upon the passage of an upward blast of gas through said vent in said second septum into said conduit.

9. Apparatus for the heat exchange of fluids in the presence of pebbles which comprises in combination an upright closed cylindrical vessel having a gas outlet at the top and a gas inlet at the

bottom, a first perforate septum positioned in the upper portion of said vessel forming an upper chamber therein and adapted for gradually passing pebbles therethrough over the entire cross-section of said vessel while maintaining a substantial layer of pebbles thereon, a second funnel-shaped imperforate septum having a vent in the center for the passage of gas therethrough and positioned in the lower portion of said vessel so as to form a lower chamber below said second septum for the combustion of fuel therein and an intermediate chamber between said first and second septa, an elongated conduit extending from the lower portion of said upper chamber through said first septum and terminating in said intermediate chamber directly above and adjacent said vent so as to effect the passage of pebbles from the bottom of said intermediate chamber into and through said conduit to said upper chamber upon the passage of an upward blast of gas through said vent into said conduit, means for introducing feed gas into the upper portion of said intermediate chamber, means for withdrawing effluent gas from the lower portion of said intermediate chamber, and means for preventing the passage of pebbles through said outlet at the top of said vessel.

10. Apparatus for the heat exchange of fluids in the presence of pebbles which comprises in combination an upright closed cylindrical vessel having a gas outlet at the top and a gas inlet at the bottom, a first perforate septum positioned in the upper portion of said vessel forming an upper chamber therein and adapted for gradually passing pebbles therethrough over the entire cross-section of said vessel while maintaining a substantial layer of pebbles thereon, a second funnel-shaped imperforate septum having a vent in the center for the passage of gas therethrough and positioned in the lower portion of said vessel so as to form a lower chamber below said second septum for the combustion of fuel therein and an intermediate chamber between said first and second septa, an elongated conduit extending from the lower portion of said upper chamber through said first septum and terminating in said intermediate chamber directly above and adjacent said vent so as to effect the passage of pebbles from the bottom of said intermediate chamber into and through said conduit to said upper chamber upon the passage of an upward blast of gas through said vent into said conduit, means for introducing feed gas into said intermediate chamber, and means for withdrawing an effluent from said intermediate chamber.

11. A method of heating a gas by direct contact with hot pebbles which comprises burning a combustible mixture, passing a blast of the resulting gaseous mixture through an orifice into the lower end of a narrow elongated vertical confined zone directly above said orifice so as to heat and entrain pebbles from the area surrounding said orifice and the lower end of said zone, thereby lifting the resulting hot pebbles through said zone into an upper expanded zone; passing a gas through said upper zone in direct heat exchange with said pebbles; maintaining a compact layer of pebbles in the lower portion of said upper zone while simultaneously passing pebbles by gravity through a plurality of paths distributed over the bottom of said upper zone to a subjacent zone surrounding said narrow vertical confined zone, thereby passing freely falling pebbles over substantially the entire horizontal cross section of said subjacent zone to a bed of same surrounding

said lower end of said narrow zone; and passing a gas through said subjacent zone in direct heat exchange with said freely falling pebbles.

12. A method of heating a gas by direct contact with hot pebbles which comprises burning a combustible mixture, passing a blast of the resulting gaseous mixture through an orifice into the lower end of a narrow elongated vertical confined zone directly above said orifice so as to heat and entrain pebbles from the area surrounding said orifice and the lower end of said zone, thereby lifting the resulting hot pebbles through said zone into an upper expanded heating zone; contacting said hot pebbles in said upper zone with a gas to be heated thereby heating said gas; withdrawing and collecting an effluent from said upper zone; maintaining a compact layer of pebbles in the lower portion of said upper zone while simultaneously passing pebbles by gravity through a plurality of paths distributed over the bottom of said upper zone to a subjacent zone surrounding said narrow vertical confined zone, thereby passing freely falling pebbles over substantially the entire horizontal cross section of said subjacent zone to a bed of same surrounding said lower end of said narrow zone; and withdrawing gaseous mixture from said subjacent zone.

13. A method of heating gas by direct contact with hot pebbles which comprises burning a combustible mixture; passing a blast of the resulting gaseous mixture through an orifice into the lower end of a narrow elongated vertical confined zone spaced apart vertically from said orifice and extending to an expanded upper zone, thereby entraining pebbles from the area surrounding said orifice and the lower end of said zone and simultaneously heating and lifting the resulting hot pebbles through said zone into said upper expanded zone; withdrawing gaseous mixture from said upper zone; maintaining a compact layer of pebbles in the lower portion of said upper zone while simultaneously passing pebbles from said layer by gravity through a plurality of paths distributed over the bottom of said upper zone to a subjacent zone surrounding said narrow vertical confined zone, thereby passing freely falling pebbles over substantially the entire horizontal cross section of said subjacent zone to a bed of same surrounding said lower end of said narrow zone; introducing feed gas to said subjacent zone in direct heat exchange with said freely falling pebbles and withdrawing and collecting an effluent from said subjacent zone.

14. A method for conversion of hydrocarbons which comprises passing a blast of hot combustion gas through an orifice into the lower end of a narrow vertical elongated confined zone directly over said orifice so as to heat and entrain pebbles from the area surrounding said orifice and the lower end of said zone, thereby ejecting the resulting hot pebbles through said zone into an upper expanded conversion zone while retaining said combustion gas in a subjacent zone surrounding said narrow zone; contacting the hot pebbles in said conversion zone with hydrocarbon gas so as to heat and convert the same to desirable product; withdrawing and recovering an effluent from said conversion zone; maintaining a compact layer of pebbles in the bottom of said conversion zone while simultaneously passing pebbles to said subjacent zone by gravity through a plurality of paths distributed over the bottom of said conversion zone, thereby passing freely falling pebbles through said subjacent zone in direct heat exchange with said combustion gas to a bed of

same surrounding said lower end of said narrow zone for reheating and recirculating to the conversion zone; and withdrawing combustion gas from said subjacent zone.

15. A method for conversion of hydrocarbons which comprises passing a blast of gas comprising hydrocarbon through an orifice into the lower end of a narrow vertical elongated confined zone spaced apart vertically from said orifice so as to entrain pebbles from the area surrounding said orifice and the lower end of said zone, thereby ejecting the pebbles through said zone into an upper expanded pebble heating zone while retaining said hydrocarbon gas in a subjacent conversion zone surrounding said narrow zone; contacting the pebbles in said pebble heating zone with hot combustion gas so as to heat said pebbles to a temperature above a predetermined conversion temperature; withdrawing combustion gas from said pebble heating zone; maintaining a compact layer of pebbles in the bottom of said pebble heating zone while simultaneously passing pebbles from said layer through a plurality of paths distributed over the bottom of said pebble heating zone to said subjacent conversion zone; gravitating said pebbles through said subjacent conversion zone in contact with the hydrocarbon gas therein, thereby heating and converting said hydrocarbon and simultaneously returning said pebbles to a bed of same surrounding said lower end of said narrow zone for recirculating to the pebble heating zone; and withdrawing and collecting an effluent from said subjacent conversion zone.

16. A method for conversion of hydrocarbons which comprises passing a blast of hot combustion gas through an orifice into the lower end of a narrow elongated confined zone directly over said orifice so as to heat and entrain pebbles from the area surrounding said orifice and the lower end of said zone, thereby ejecting the resulting hot pebbles through said zone into an upper expanded separation zone; withdrawing combustion gas from said upper zone; collecting hot pebbles in the bottom of said upper zone and passing the same by gravity through a plurality of paths distributed over the bottom of said upper zone to a subjacent conversion zone surrounding said narrow vertical zone, thereby passing freely falling pebbles through said conversion zone to a bed of same surrounding said lower end of said narrow zone for reheating and recirculating to said upper separation zone; introducing hydrocarbon gas into said conversion zone into contact with the gravitating hot pebbles therein so as to effect conversion thereof; and withdrawing a conversion effluent from said conversion zone.

17. Apparatus for the treatment of a gas in the presence of pebbles which comprises in combination an upright, elongated, cylindrical vessel having a gas outlet in the top section and an orifice in the bottom thereof; a perforate septum having a central vent of larger size than the other perforations in said septum, said septum being positioned across the upper portion of said vessel so as to form an upper and a lower chamber therein and being adapted for gradually passing pebbles downwardly therethrough uniformly over the horizontal cross section of said vessel except at said vent; a plurality of conduits opening into said lower chamber through the cylindrical walls of said vessel for introducing to and withdrawing gas from said lower chamber; and an elongated open ended conduit of relatively small cross-sectional area extending between said vent and

said orifice in close spaced-apart relation at its lower end to said orifice so as to provide a passageway for said pebbles to flow into the end of said conduit from the surrounding space and adapted so as to effect the passage of pebbles from the bottom of said lower chamber into and through said conduit into said upper chamber upon the passage of an upward blast of gas through said orifice.

18. Apparatus for the treatment of fluid in the presence of heat-exchange pebbles which comprises in combination an upright elongated cylindrical vessel having a gas outlet in the upper portion and gas inlet orifice in the bottom thereof, said bottom being cupped to cause flow of said pebbles toward said orifice; a transverse perforate septum in said vessel intermediate the ends thereof dividing said vessel into an upper chamber and a lower chamber extending from said septum to the lower end of said vessel, the perforations in said septum providing pebble passageways from said upper to said lower chamber; a vent in said septum larger than said perforations providing a passageway for pebbles upwardly therethrough; a gas inlet in said upper chamber; a gas outlet in said lower chamber; and an elongated conduit of relatively small cross-section open at both ends and fixed in said lower chamber in alignment with said orifice and said vent, its lower end approaching the upper end of said orifice in spaced-apart relation thereto so that a blast of gas injected upwardly through said orifice entrains and lifts pebbles from the lower end of said lower chamber to said upper chamber.

19. Apparatus for the treatment of a fluid in contact with pebbles, which comprises in combination an upright, elongated cylindrical vessel having a gas outlet at the top and an orifice in

the bottom thereof; a perforated septum having a central vent larger than the other perforations in said septum for the passage of pebbles upwardly therethrough, said septum being positioned across the upward portion of said vessel and forming an upper and lower chamber therein and being adapted for gradually passing pebbles downwardly therethrough uniformly over the horizontal cross-section of said vessel except at 5 said vent while maintaining multiple layers of pebbles thereon; means for introducing gas into said upper chamber; means for removing gas from said lower chamber; and an elongated open-ended conduit of relatively small cross-sectional 10 area positioned in said lower chamber in alignment with said vent and said orifice extending therebetween in close spaced-apart relation at its lower end to said orifice so as to provide a passageway for said pebbles to flow into the end of 15 said conduit from the surrounding space, and adapted so as to effect the passage of pebbles from the bottom of said lower chamber into and through said conduit into said upper chamber upon the passage of an upward blast of gas 20 through said orifice.
